(57) **CLAIM**

The ornamental design for a phone case, as shown and described.

DESCRIPTION

FIG. 1 is a front perspective view of the phone case showing my new design;

FIG. 2 is a back perspective view thereof;

FIG. 3 is a bottom view thereof;

FIG. 4 is a top view thereof;

FIG. 5 is a left side view thereof;

FIG. 6 is a right side view thereof;

FIG. 7 is a front view thereof;

FIG. 8 is a back view thereof; and,

FIG. 9 is a front perspective view thereof, shown without symbolic breaks for ease of illustration and in condition of use with a phone disclosed in broken lines to illustrate an environment.

The broken lines showing a phone in FIG. 9 represent environmental structure and form no part of the claimed design.

The break lines shown in FIGS. 1-4 and 7-8 are included to show a symbolic break and the appearance of any portion of the article between the break lines forms no part of the claimed design.
